UNITED STATES PATENT OFFICE.

WILLIAM S. LEE, OF DETROIT, MICHIGAN.

EXPLOSION-ENGINE.

1,033,911.

Specification of Letters Patent. Patented July 30, 1912.

Application filed January 26, 1911. Serial No. 604,724.

To all whom it may concern:

Be it known that I, WILLIAM S. LEE, a citizen of the United States, and a resident of Detroit, in the county of Wayne and State of Michigan, have invented a new and useful Explosion-Engine, of which the following is a specification.

This invention relates to two-cycle engines having pistons of two diameters, one of the diameters working in the explosion chamber and the other in the compression chamber, and its object is to provide an explosion engine wherein the waste of explosive mixture, because of improper timing of the exhaust relative to the intake, shall be eliminated, and in which a sleeve-like valve shall positively control the passage of the gases into and out of the explosion, storage and compression chambers.

In the accompanying drawings, Figure 1 is an elevation of the engine. Fig. 2 is a central vertical cross section at right angles to the shaft. Fig. 3 is a similar cross section on the line of the shaft.

Similar reference characters refer to like parts throughout the several views.

The stationary portions of the engine shown in the drawings are a base 1 having bearings 2 for the crank-shaft 3, the combined frame and cylinder 4, and the cylinder head 5. The head and cylinder have the usual water passages 6 and 7. The cylinder has an intake opening 8 which communicates with the carburetor and with an annular intake passage 9. It is also provided with an exhaust opening 10 which connects to the annular exhaust passage 11. A spark plug 12 may screw into the threaded hole 13 in the head. An annular storage chamber 14 surrounds the cylinder at the joining line between its smaller or explosion portion 15 and the larger or compression portion 16.

Slidable within the two portions 15 and 16 of the cylinder is the two-diameter valve-sleeve, formed by the connected cylinders 18 and 19. This valve-sleeve is provided with the discharge ports 20, the inlet-ports 21, and the compression control-ports 22, which will be termed compression ports. The cylinder 15 has exhaust ports 23, while the cylinder 16 has intake ports 24 and transfer ports 25. These ports will all be spaced around the cylinders and valve-sleeves, and their num-

ber, dimensions and proportions will vary according to the engine-duty and the fuel. 55

The crank shaft 3 has eccentrics 28 secured to it on either side of the crank 29, and eccentric rods 30 connect to the pins 31 carried by the ears 32 which extend down from the valve-sleeve 19. Any other desired 60 device to operate the valve sleeve may be employed.

The piston is formed in two parts, a working piston 33 which fits the smaller part 18 of the valve-sleeve, and the compression piston 34 which fits the larger part 19 of the valve-sleeve. The piston carries a pin 35, which passes through the upper end of the connecting rod 36, the lower end of which engages the crank pin 37. 70

The lead of the eccentric may vary, depending upon the duty and the fuel of the engine. In the drawing, a lead of about twenty two degrees is shown. With the parts as shown in Fig. 3, it will be noticed 75 that the storage chamber, and the transfer port are in communication with the compression chamber 38 above the piston 34, at the beginning of the down-stroke. All the compressed vapor has therefore had a chance 80 to pass into the storage chamber which may be of any desired size. As the movement of the valve sleeve is quite rapid at this period, the transfer port will be closed immediately after the piston begins to descend. 85

For practically the first one-third of the working stroke, the piston 34 travels at about the speed of the valve-sleeve, but during practically the next one-third of the stroke, the piston travels much faster than 90 the valve-sleeve. As a result, by the time the compression-port registers with the intake-port, the compression chamber is rapidly increasing in size, and when the ports do register, a partial vacuum will be 95 present and the explosive mixture will rush in from the carburetor, until the lead of the eccentric causes the compression port and the intake port to separate which occurs at about the time the piston reaches the bottom 100 of its stroke. The upward movement of the piston will then compress the charge in the compression chamber 38 until the compression port registers with the transfer port as shown in Fig. 3. The compressed charge 105 will pass into and remain in this storage

chamber until the inlet port passes below the bore of the cylinder 15, and until the piston 33 uncovers this inlet port, which occurs just about when the valve-sleeve 5 has reached the lower limit of its movement. As a result, the inlet port is open but a short time.

The exhaust occurs when the valve-sleeve 18 has descended sufficiently to cause the 10 charge port 20 to register with the exhaust port 23, which is at about the time the piston has passed through three fourths of its working stroke. The exhaust occurs 15 slightly before the inlet port opens so that there will be no pressure in the working cylinder when the inlet port opens. The exhaust ceases just before the explosive mixture has had time to fill the working cylinder whereby loss of the mixture is prevented. The proportions between the diameters of the two pistons 33 and 34 will depend upon the duty, the speed and the fuel, and primarily upon the compression pressure desired.

25 Many changes in the details of construction of these engines may be made by those skilled in the art without departing from the spirit of my invention.

Having now explained my construction, 30 what I claim as my invention and desire to secure by Letters Patent is:—

1. In an explosion engine, the combination of a cylinder having bores of two diameters, a slidable valve-sleeve mounted therein and having corresponding external diameters and a bore of two diameters, and a piston within the valve-sleeve having diameters corresponding to the bores of the valve, 35 a crank shaft, a connecting rod between the shaft and piston, and means connected to said crank-shaft for actuating the valve-sleeve.

2. In an explosion engine, the combination of a cylinder having bores of two 40 diameters, a slidable valve-sleeve mounted therein and having corresponding external diameters and a bore of two diameters, and a piston within the valve-sleeve having diameters corresponding to the bores of the valve, 45 a crank-shaft, a connecting rod between the shaft and piston, and means connected to said crank-shaft for actuating the valve-sleeve.

valve-sleeve, said cylinder and valve-sleeve having ports to permit the passage of fuel vapor and burned gases.

55 3. In an explosion engine, the combination of a cylinder, a valve-sleeve and a piston, each formed with two diameters, said cylinder having a chamber in its wall for the storage of fuel vapor, said valve-sleeve 60 and cylinder having ports for the passage of fuel vapor and burned gases, a shaft, and means connected to said shaft whereby the piston may actuate the valve sleeve.

65 4. In an explosion engine, the combination of a cylinder having bores of two diameters, a slidable valve-sleeve mounted therein and having corresponding external diameters and a bore of two diameters, and a piston within the valve-sleeve having diameters corresponding to the bores of the valve, 70 and means to actuate the valve-sleeve, said cylinder having intake and exhaust ports controlled by said valve-sleeve and a storage chamber and an annular passage for explosive mixtures formed in its walls, said walls having ports controlled by the larger portion of the valve-sleeve and adapted to communicate with an annular space within the larger bore of the valve-sleeve and surrounding the smaller diameter of the piston.

75 5. In an explosion engine, the combination of a cylinder having exhaust ports at its end farthest from the crank shaft and intake ports at its end nearest the crank 80 shaft and an inlet passage and storage chamber in its wall at its end nearest the crank shaft, a valve-sleeve slidable therein and having inlet and exhaust ports and ports to connect alternately with openings 85 into the inlet passage and into the storage chamber, a piston slidable within the valve-sleeve, a crank-shaft, a connecting rod between the piston and crank-shaft, and means connected to the crank-shaft for actuating the valve sleeve.

90 In testimony whereof I have signed this specification in the presence of two subscribing witnesses.

WILLIAM S. LEE.
